UNITED STATES PATENT OFFICE.

JOSEPH N. ROYAL, OF BUFFALO, NEW YORK, ASSIGNOR TO F. N. BURT COMPANY, LIMITED, OF TORONTO, CANADA, A CORPORATION OF ONTARIO, CANADA.

COMPOSITE-FIGURE CONSTRUCTION.

Application filed February 28, 1927. Serial No. 171,466.

This invention relates to improvements in the construction of figures or toys, and more particularly in some of its details to improvements in such figures of composite seamless construction of impacted fibrous material, and being utilizable as a container or receptacle.

It is the general object of the invention to provide a composite figure or toy of the class mentioned of improved structural form whereby it may be advantageously and inexpensively manufactured of a fibrous material such, for example, as wood pulp, and at the same time be of novel and attractive appearance, and an interior compartment to adapt it to serve as a container.

A further object of the invention is to provide an improved composite figure or toy wherein the component parts thereof mutually cooperate to provide a receptacle of relatively large capacity and of unique and pleasing appearance.

A further object is to devise an improved construction for composite figures wherein the component parts are relatively disposed and integrally united in such manner as to mutually reinforce the structure.

Another object is to devise an improved process of making a composite article having seamless walls of impacted fiber.

Other objects will be in part pointed out in connection with the following detailed disclosure of an illustrative but preferred embodiment of the invention, and will be in part obvious in connection with said disclosure.

The invention accordingly comprises an article of manufacture possessing the features, properties, and the relation of elements which will be exemplified in the article hereinafter described and the scope of the application of which will be indicated in the claims.

For a more complete disclosure of the nature and objects of the invention, reference is had to the following detailed description and to the accompanying drawings, in which:

Fig. 1 is a side elevation of a figure embodying the invention.

Fig. 2 is a central vertical section from forward to rear of the figure, and

Fig. 3 is a horizontal section substantially on the line 3—3 of Fig. 2 looking downwardly.

Referring to the drawing for a detailed description of the illustrative embodiment of

the invention, the article is there shown as comprising a body 10 simulating an animated object. Attached to this figure, as upon the back thereof, is a receptacle 11. In the embodiment shown the figure is in the form of a standing person made up to represent a Santa Claus, and the receptacle is in the form of a pack carried by the figure, but it will be understood that the figure and receptacle may take other forms. Both the figure and the receptacle are provided with interior cavities 12 and 13, respectively, merging and combining with each other to form a single interior compartment which may be utilized for the reception and support of any desired articles such as toys or gifts. A receiving compartment of relatively large dimensions as compared with the size of the pack is thus provided. An opening 14 is formed in the top of the pack, being in communication with the receiving compartment to provide a passageway for receiving or removing the articles.

A wall 15 outlines the contour or outer surface of the Figure 10, and a wall 16 similarly outlines the contour of the receptacle 11. These walls join with each other, as shown on lines extending longitudinally and transversely of the article and are discontinuous at the line of juncture thereof; that is, the walls follow the respective contours both of the figure and receptacle to the wall intersection line beyond which both the figure wall and the receptacle walls are discontinuous, each being merged with the other along said line. The wall juncture line is positioned so as to lie relatively far outwardly toward the sides of the article and relatively low down thereon so as to provide a large communicating opening or passageway between the interior cavities of the figure and receptacle so as to practically unite these two cavities to form a single interior receiving compartment. It will be seen that this passageway is defined by the line of juncture between the walls of the figure and receptacle.

The walls 15 and 16 are preferably made integral with each other, and are seamless throughout. That is, the walls throughout their extent are constructed of seamless material, the merging of the walls of the figure and receptacle at the juncture thereof being integral and seamless. Thus the walls at the juncture thereof form integral seamless continuations of each other. The merging lines

between the walls of the figure and receptacle are positioned somewhat inwardly of the extreme outer surfaces of the figure and receptacle so as to provide longitudinal inwardly disposed reinforcing ribs 17 and a similar transverse inwardly disposed rib 18 at the lower part of the article. This feature is of importance since it provides integral longitudinal and transverse reinforcement for the article and permitting quite a thin wall, and construction of a fragile material, yet furnishing sufficient rigidity and stiffness for amply supporting the article with its load.

The composite article is preferably made complete in one piece, the walls thereof being free from seams or joints. The material of the walls is preferably impacted fiber. The walls are advantageously formed by introduction of wood or like pulp of fibrous material suspended in water to a foraminous mould shaped to conform to the combined figure and receptacle. The liquid suspended pulp fibers are introduced into the mould under pressure, whereupon the liquid seeps or is forced through the apertures in the mould walls while the fibers are caught and deposited on the inner surface of the mould.

The pulp bearing liquor is preferably introduced into the mould at a part thereof coincident with the receptacle opening 14 so as to avoid the formation of an opening at any such part of the article as might tend to mar its construction or appearance. Also the current of pulp liquor entering the opening 14 can be directed in a straight line substantially longitudinally of the figure or slightly diagonally from rear to front thereof. This avoids directing the current directly against a closely adjacent part of the mould, or formation of eddy currents within the mold, in such a manner as might wash away the fibers from said adjacent parts of the mould walls, thus preventing fiber deposit and causing thin or defective walls. This fault is entirely avoided by the described arrangement. A vacuum may be applied to the mould, either alone or in combination with internal mould pressure, to cause deposit of the fibers on the mould walls; centrifugal or vibratory action of the mould may also be utilized for this purpose.

Due to the pressure of the liquid within the mould, or to the action of some other agency such as mentioned, the fibers are deposited and lightly impacted upon the mould walls so as to form a fibrous layer over the inner mould surface. When the fibers have thus deposited sufficiently to form the article wall of the desired thickness, introduction of the pulp-bearing liquid is discontinued and the article thus deposited is then dried as by introducing dry steam or heated air into the mould. The steam or air may be introduced under pressure sufficient to still further impact the fibers so as to form a wall of firm

and tough structure. It will be seen that the walls thus formed are integral and seamless throughout and that the merging of the walls of the figure and receptacle is wholly free from seams. The article, therefore, while being susceptible of manufacture by a simple and inexpensive process, is strong and durable.

Since certain changes may be made in the above article, and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A composite article including a figure simulating an animated object and a receptacle integrally united with said figure, said article having seamless enclosing walls outlining the contours of the figure and receptacle, said figure and receptacle having interior cavities merging and combining with each other and arranged in extension of each other to provide an interior receiving compartment bounded by the said walls, and said article having a receiving opening in communication with said receiving compartment.

2. A composite article including a figure simulating an animated object and a receptacle integrally united with said figure, said article having walls outlining the contours of the figure and receptacle, said figure and receptacle having interior cavities merging and combining with each other and arranged in extension of each other to provide an interior receiving compartment, and said article having a receiving opening in communication with said receiving compartment, the walls of said figure and receptacle joining each other and being integrally merged at the line of juncture thereof forming integral continuations of each other and enclosing said receiving compartment.

3. A composite article including a figure simulating an animated object and a receptacle united with said figure, said article having walls outlining the contours of the figure and receptacle, said figure and receptacle having interior cavities merging and combining with each other and arranged in extension of each other to provide an interior receiving compartment, and said article having a receiving opening in communication with said receiving compartment, the walls of said figure and receptacle joining each other and

- being integrally merged at the line of juncture thereof, forming integral continuations of each other and enclosing said receiving compartment, and the merging of said walls 5 forming longitudinal and transverse reinforcing ribs for the article.
4. A composite article including a figure simulating an animated object and a receptacle united with said figure, said article having enclosing walls outlining the contours of the figure and receptacle, said figure and receptacle having interior cavities merging and combining with each other and arranged in extension of each other to provide an interior 10 receiving compartment, said walls joining and integrally merging with each other and being discontinuous on the line of juncture thereof at the place of merging of said cavities.
5. A composite article including a figure simulating an animated object and a receptacle united with said figure, said article having enclosing walls outlining the contours of the figure and receptacle, said figure and re-
- ceptacle having interior cavities merging and combining with each other and arranged in extension of each other to provide an interior receiving compartment, said walls joining and integrally merging with each other and being continuous on the line of juncture thereof to define a passageway between said cavities, and the merging line of said walls forming longitudinal and transverse reinforcing ribs for the article.
6. A composite article including a figure simulating an animated object and a receptacle united with said figure, said figure and receptacle having walls of seamless impacted fibrous material joining and being integral with each other at the line of juncture thereof, said figure and receptacle having interior cavities merging with each other so as to unite said cavities into a common interior receiving compartment and the place of said merging being defined by said line of juncture.

In testimony whereof I affix my signature.
JOSEPH N. ROYAL.
